GAP MILL CONTROL

John H. Friedman, Tiffin, Ohio, assignor to The National Machinery Company, Tiffin, Ohio, a corporation of Ohio

Application October 4, 1952, Serial No. 313,159

3 Claims. (Cl. 80—26)

This invention relates to rolling mills and more particularly to control mechanisms for gap mills of the type constructed to operate in a cyclic manner, wherein the rolls are stopped after each revolution of the rolls.

In prior art roll gap mills, the rolls were continuously rotated and the operator inserted a blank through the gap against a stop gauge beyond the rolls. This type of mill required a great deal of skill on the operator's part since the timing of the insertion of the blank between the rolls was critical. A further disadvantage was present since the gaps had to be formed along the large portion of the periphery of the rolls to provide time to allow the operator to insert the blank. Since the gap was present in a large portion of the roll large rolls were necessary to provide the circumferential length necessary to roll a given blank. Since the rolls were necessarily large in this type of machine, the torques necessary to operate the rolls were large, and the frames were necessarily heavy.

In recent developments in the rolling mill art improvements have been made which permit the use of smaller rolls to roll a given blank. This has been accomplished by reducing the amount of gap necessary to permit the insertion of the blank between the rolls. In such mills the rolls are stationary at the gap portion while the blank to be rolled is arranged between the rolls. The rolls are turned one revolution so that the resulting rolled article is shaped by the roll dies and the rolls are then brought to a stop for the insertion of the next blank. This type of mill has provided a gap rolling mill which can be operated by relatively unskilled operators since the rolls are stationary at the time the blank is inserted between the rolls. A mill of this type is disclosed in my copending application Serial No. 168,218 filed June 15, 1950, now Patent No. 2,634,144.

In gap mills of the improved variety described above the rotation of the rolls has been controlled by the use of a foot treadle manipulated by the operator of the mill after the blank to be rolled is arranged in rolling position between the rolls. A gauge is provided behind the rolls against which the operator positions the blank. When the blank is in position against the blank gauge the operator presses the foot treadle turning the rolls through one revolution.

With the increase in use of gap rolls due to the above advances there has been an increase in the size of the mills and it has required greater skill on the part of the operator to manipulate the blank to make sure that it is against the stock gauge and in proper position for rolling. The advent of larger machines has also resulted in rolling larger blanks which, in turn, require larger rolls. These larger rolls, of course, require greater torques to roll a blank so again it is important to reduce the gap size necessary thereby permitting a reduction in the size of the roll.

The present invention is directed to a rolling mill of the gap type wherein the placing of the blank in position for rolling automatically causes the rolls to start and

2

wherein the blank is not inserted through the gap in the rolls prior to the rolling operation. A stock trip is provided across which the blank is moved and is positioned so that the rolls begin to operate when the end of the blank is properly positioned in the gap of the rolls. By employing a stock trip according to this invention it is also possible to automatically feed the blanks into the gaps thereby eliminating the necessity of hand operation. However, a machine embodying this invention will operate equally as well with manual feeding.

It is a principal object of this invention to provide a gap roll in which the rolls are automatically actuated when the blank to be rolled is in the proper position.

It is a further object of this invention to provide a gap roll wherein the blank need not be inserted through the gap before the rolls are actuated thereby reducing the size of gap necessary.

It is a still further object of this invention to provide a gap roll capable of being mechanically fed.

It is another object of this invention to provide a gap roll having a clutch and a brake and having a trip for engaging the blank to be rolled wherein the movement of the trip by the release of the engagement with the blank actuates the rolls when the blank is in position to be rolled.

Further objects and advantages will appear from the following description and drawings, wherein:

Fig. 1 is a perspective view of a gap rolling mill embodying this invention;

Fig. 2 is a side elevation of the stock gauge assembly;

Fig. 3 is a view partially in section of the one shot valve;

Fig. 4 is a schematic drawing of the gap roll control circuit; and

Fig. 5 is a schematic drawing of an electrical embodiment of the gap roll control.

In a preferred embodiment of this invention the rolling mill is provided with a clutch and brake arranged between the roll shafts and the fly wheel which are adapted for pneumatic operation. The brake and clutch are arranged so that the clutch is engaged and the brake is released and when the clutch is disengaged the brake is engaged. A stock trip is located on the rear blank support. As the blank is moved along the rear blank support toward the rolls it engages and depresses the trip. The control circuit is arranged so that when the blank passes beyond the trip thereby releasing the engagement between the blank and the trip the clutch is engaged and the brake is released thereby actuating the rolls. A cam mounted for rotation with the roll shaft disengages the clutch and engages the brake after one revolution of the rolls thereby completing the cycle of operation and preparing the machine for the next cycle.

Referring to the drawings, the mill incorporating this invention is shown in Fig. 1 at 9 and preferably includes a pair of cooperating gap rolls 10 and 11 which are geared to each other as at 12 and 13. A front blank support 14 is arranged on the discharge side of the rolls and a similar rear blank support 16 is carried by the mill on the other side of the rolls. A blank guide 17 is mounted on the support 16 to guide the blank as it is moved toward the rolls. The mill 9 includes a clutch and brake arranged so that the continuously rotating fly wheel 18 may be engaged so as to transmit fly wheel rotation to the rolls 10 and 11. For purposes of simplification the brake structure and the clutch structure have not been shown but are described in detail in my copending application Serial No. 168,218 filed June 15, 1950, now Patent No. 2,634,144.

One embodiment of the control circuit embodying this invention is shown diagrammatically in Fig. 4 and includes a trip valve or sensing control 21, a one shot or

sequence valve 22, a reset cylinder 23, a main control valve 24, and a clutch control valve 26. Cams 27 and 28 are associated with the main control valve 24 and the one shot valve 22 respectively and are attached for rotation on the mill.

The trip valve 21 is connected to a source of air pressure 31 by the line 32 and is arranged to engage the trip 33. The upper end of the trip 33 projects above the surface of the blank support 16 and is arranged to engage the blank 34 as it slides along the blank support 16 toward the roll 11. The spring loaded trip return 36 urges the trip to its normal position shown in Fig. 2 and opposes the movement of the trip 33 when engaged by the blank 34. When the trip is in its normal position the trip valve or sensing control 21 provides communication between the pressure inlet line 32 and the outlet line 37.

When the blank 34 engages and depresses the trip 33 the trip moves to the position shown in the dotted line in Fig. 2 permitting the plunger 38 to move axially in the trip valve 21 thereby actuating the valve and isolating the inlet line 32 while creating communication between the outlet line 37 and the atmospheric exhaust line 39. For the details of construction of the trip valve 21 reference may be made to my co-pending application Serial No. 210,734 filed February 13, 1951, now Patent No. 2,615,355.

The one shot or sequence control valve 22 embodies a body 41 having an axial bore 42 in which is fitted a cylinder wall sleeve 43. A second axial bore 44 larger than the bore 42 opening thereto is also formed in the body 41. A second cylinder wall sleeve 46 is secured in the second bore 44. An axial reciprocable shaft 47 is positioned within the cylinders formed by the sleeves 43 and 46 passing through the apertured cap 48 which is attached to the body 41 by the bolts 49. A piston 51 is mounted for reciprocation with the shaft 47 and is provided with a flange 52 which slidably engages the walls of the second cylinder wall sleeve 46 creating fluid seal therebetween. Adjacent to the upper end of the piston 51 is a reciprocable cup shaped seal 53 mounted for reciprocation with the cylinder wall sleeve 43 creating a fluid seal therewith. A second cup shaped seal 54 is attached to the shaft 47 in a position axially removed from the seal 53. The seal 54 also reciprocably engages the cylinder wall sleeve 43 creating a fluid seal therewith. The piston 51 and the seals 53 and 54 comprise the piston assembly which reciprocates to effect the valving operation.

A spring 56 is provided in the lower body cap 57 and extends between an end flange 58 formed in the lower body cap 57 and the lower surface of the piston 51. The spring 56 is preloaded in position thereby urging the piston 51 and the piston assembly axially upward to the actuated position. Ports 59 are formed in the cylinder wall sleeve 43 and provide fluid communication between the upper cylinder 60 which is bounded by the cylinder wall sleeve 43 and the lower cylinder 62 which is bounded by the cylinder wall sleeve 46. An inlet port 63 connects the line 37 to the cylinder 60 between the seals 53 and 54.

When the piston assembly is in the reset position shown in Fig. 3 the fluid under pressure in the line 37 flows into the cylinder 60. From the cylinder 60 the fluid under pressure flows through the ports 59 around the seal 53 into the lower cylinder 62. Since the piston 51 has a larger area than the seal 54 the net resulting fluid force created by the fluid under pressure results in a downward force which opposes the spring 56 and holds the shaft 47 in the reset position. An outlet port 64 is provided in the cylinder 60 above the seal 54 and is connected to the line 66. When the trip valve 21 is operated by the blank 34 thereby exhausting the line 37 the fluid pressure within the cylinders 60 and 62 is also exhausted and the piston assembly moves to the actuated position shown in phantom in Fig. 3. When the piston and the

seals are in the actuated position the port 59 is isolated from the port 63 and the port 63 is in communication with the port 64. An exhaust port 67 is formed in the cylinder 60 above the port 64 and is in communication therewith when the seals are in the reset position.

A reciprocable block 71 is mounted on the shaft 47 above the cap 48 and is provided with a guide 72 which prevents rotational movement of the block 71 and, in turn, the shaft 47. A cam 28 is mounted for rotation with the rolls and is positioned to engage the cam follower roll 73 which is rotatably mounted in the block 71.

To insure that the one shot valve is in the reset position when air is initially admitted to the system a reset cylinder 23 with an axially reciprocable piston 76 is provided. The piston 76 is biased in the downward direction by the spring 77 which extends between the cylinder head 78 and the piston 76. Fluid under pressure is admitted to the cylinder below the piston 76 through the line 79 and creates a force against the piston 76 opposing the action of the spring 77 thereby moving the piston to the upper position shown in Figs. 3 and 4. The reset cylinder shaft 81 is mounted for reciprocation with the piston 76 and is formed with a U-shaped end portion 82 arranged to engage the extension 83 formed on the block 71. When the valve 84 is closed fluid pressure within the reset cylinder 23 is released and the piston 76 is moved axially downwardly by the spring 77. The surface 86 then engages the extension 83 and moves the piston assembly downward against the spring 56 to the reset position.

The main control valve 24 is connected to the source of fluid pressure 31 and is arranged so its normal position isolates the source of pressure 31 from the brake and the clutch control valve 26. The main control valve 24 is also connected to the line 66 and is arranged so that fluid pressure in this line will cause the valve to actuate and create communication between the source of fluid pressure 31 and the brake line 87 and the clutch control valve line 88. The structure of the main control valve is shown in detail in my co-pending application Serial No. 210,734, filed February 13, 1951, now Patent No. 2,615,355.

The main control valve 24 is also provided with an extension 93 connected by linkage to the cam follower 94 which engages the cam 27. The cam which rotates with the rolls is adapted to operate the follower 94 and thereby maintain the control valve in the actuated position until one revolution is completed.

The clutch control valve 26 is connected to a source of fluid pressure 31a and is arranged so that the normal position of the valve isolates fluid pressure. The clutch control valve 26 is also connected to the clutch control valve line 88 and is arranged so that fluid pressure within this line causes the valve to be actuated and create fluid communication between the fluid pressure source 31a and the clutch pressure line 89. When the clutch control valve is in the normal position fluid communication is established between the clutch pressure line 89 and the exhaust ports 91. The details of the clutch control valve 26 are shown in my co-pending application Serial No. 210,734, filed February 13, 1951, now Patent No. 2,615,355.

In operation the valve 84 is opened allowing fluid pressure to flow from the fluid pressure source 31 through the lines 32 into the trip valve 21. From the trip valve 21 the fluid pressure flows through the line 37 and the port 63 into the cylinder 60 within the one shot valve 22. Prior to the opening of the valve 84 the reset cylinder 23 is exhausted. The spring 77 within the reset cylinder therefore moves the piston 76 and the one shot valve shaft 47 downwardly. Since the reset cylinder assures that the one shot valve is in the reset position at the time of the opening of the valve 84 the fluid under pressure flowing through the line 37 enters the port 63 and flows through the port 59 into the cylinder 62 thereby contin-

ting to hold the one shot valve in the reset position. As the fluid flows through the line 79 into the reset cylinder 23 the piston 76 moves upwardly against the spring 77 and disengages the surface 86 on the extension 83.

As the blank 34 is moved across the trip 33 the trip is depressed actuating the trip valve 21 thereby isolating the line 32 and creating fluid communication between the line 37 and the exhaust line 39. Since the fluid pressure within the cylinders 60 and 62 is exhausted through the line 37 the one shot valve moves to the actuated position shown in phantom in Fig. 3, creating fluid communication between the lines 66 and 37.

When the blank 34 is moved toward the roll 11 beyond the trip 33, thereby indicating that the blank is in position, the trip 33 is released and returns to its normal position under the force of the spring loaded trip return 36 thereby re-establishing fluid communication between the lines 32 and 37. Since the one shot valve at this time provides communication between the lines 37 and 66 the fluid pressure flows through the one shot valve up to the main control valve 24. When the one shot valve is in this position the ports 59 are isolated by the seal 53 preventing fluid flow into the cylinder 62 so the one shot valve remains in the actuated position.

The fluid pressure within the line 66 actuates the main control valve establishing fluid communication between the fluid pressure source 31 and the lines 87 and 88. The fluid pressure within the line 88 causes the brake to release at this time and the fluid pressure within the line 88 causes the clutch control valve to actuate creating fluid communication between the pressure source 31a and the line 89. The fluid pressure within the line 89 causes the clutch to engage starting the rolls.

As the rolls rotate the cam 27 also rotates causing the cam follower to operate the extension 93 thereby holding the main control valve 24 in its actuating position. The cam 28 also rotates with the rolls and is proportioned to operate against the cam follower rolls 73. After the cam 27 has rotated to a point it holds the main control valve 24 in the actuated position. The action of the cam 28 causes the block 71 to move the one shot or sequence valve to the reset position thereby resetting the valve. When the one shot valve 22 is reset by the cam 28 fluid communication is created between the line 37 and the port 59 causing the one shot valve to remain in the reset position. At the same time fluid communication is established between the line 66 and the exhaust port 67 so the line 66 is exhausted to atmospheric pressure.

When the rolls rotate through one complete revolution the cam 27 assumes the position shown in Fig. 4 and the main control valve 24 returns to its normal position thereby isolating the fluid pressure source 31a from the lines 77 and 78. When the line 87 is isolated from the pressure source the brake again engages stopping the rolls. At the same time the clutch control valve 26 returns to its normal position isolating the fluid pressure source 31a from the line 89 thereby creating fluid communication between the line 89 and the exhaust ports 91 causing the clutch to disengage.

In the corresponding electrical embodiment of this invention shown in Fig. 5, the overall operation is identical with that described above. However, an electrical system is utilized to control the operation of the main control valve.

Since in this embodiment the controlling force is electrical instead of fluid under pressure the power enters the system through the power lines 101 through the main power switch 102. A trip switch 103 is mounted for engagement with the blank in the same manner as the trip valve 21 and the trip 33. The trip switch 103 embodies a normally closed contact 104 and a normally open contact 106.

A solenoid operated switch 107 replaces the one shot valve of the fluid embodiment and is provided with a spring 108 to hold the switch in either the opened or

closed position. An armature is operatively attached to the contact element and is adapted to be actuated by the solenoid coils 111 and 112. A cam operated holding switch 113 is actuated by the cam 114 which is mounted for rotation with the rolls. A cam operated reset switch 116 is operated by the cam 117 also attached for rotation with the rolls.

An electrically operated valve 118 is substituted for the main control valve 24 and is adapted to isolate the fluid pressure source 31a from the lines 87a and 88a in its normal position and provide fluid communication therebetween when actuated. The contact 106 is electrically connected to the coil 112 so that closing of this contact operates to close the switch 107. The cam operated switch 116 is electrically connected to the coil 111 so that closing of the switch 116 operates to open the switch 107. The normally closed contact 104 is in series with the switch 107 and is arranged so that the closing of the contacts when the switch is closed actuates the valve 118. In operation all of the elements shown in Fig. 5 are initially in the position shown therein. As the blank engages the switch 103 the contact 104 is opened and the contact 106 is closed causing the switch 107 to close. When the blank passes into the rolls beyond the switch 104 this switch returns to its normal position actuating the valve 118. At this time the clutch is engaged and the brake is disengaged as described above in the embodiment shown in Fig. 4 causing the rolls to rotate. As the rolls rotate the cam 114 rotates and thereby causes the switch 113 to close and hold the valve 118 in its actuated position. After this occurs the cam 117 closes the switch 116 thereby energizing the coil 111 opening the switch 107. When the roll has completed one revolution the switch 113 opens thereby breaking the electrical power supply to the valve 118 and causing it to return to its normal position releasing the clutch and engaging the brake thereby stopping the roll rotation. When the next blank engages the switch 104 the entire cycle is repeated.

At this time all of the elements of the control system are returned to their initial position and another blank may be fed across the trip 33 into the rolls.

Having completed a detailed description of a preferred embodiment of the present invention so that others skilled in the art may be able to understand and practice the same, I state that what I desire to secure by Letters Patent is not limited by said preferred embodiment but rather is defined in what is claimed.

What is claimed is:

- Control means for a gap mill of the cyclic one revolution type wherein a pair of cooperating gap rolls are driven through one revolution by a clutch and are stopped at the end of said revolution by a brake comprising a horizontally disposed blank feeding table mounted on the mill in alignment with the roll gap, the said table having an opening therein spaced horizontally from the roll gap, a movable trip mounted beneath said table at said opening and having its upper end normally projecting upwardly through said opening into the path of a blank being advanced along the feeding table by the operator, spring means normally urging said trip upwardly into said path, said trip being moved downwardly in response to engagement of the trip by the leading edge of a blank being advanced along said path, said trip being maintained in its lowered position by engagement with the underside of the blank being advanced along said path, said trip returning to said projecting position in response to said spring means after the trailing edge of the blank has passed beyond the trip, clutch and brake control means operably connected to said trip comprising a trip valve connected to the trip and a sequence valve connected by a conduit to said trip valve, said sequence valve having an inlet and an outlet, a spring-pressed plunger mounted for movement by said spring within the sequence valve to an open position establishing communication between the inlet and outlet and to a closed position interrupting com-

munication between said inlet and outlet, said sequence valve having a piston therein responsive to fluid pressure at the inlet when the valve is in its closed position to hold the sequence valve closed so functioning that when said trip is in its upward projecting position the sequence valve is held closed and when said trip is depressed said valve is moved to open position to vent the valve to atmosphere through the trip valve and thereafter said trip valve is moved by said trip to direct fluid pressure into the sequence valve in its open position and cam means rotating in timed relation to the rolls to restore said sequence valve to closed position.

2. Control means for a gap mill of the cyclic one revolution type wherein a pair of cooperating gap rolls are turned through one revolution in response to clutch engagement and are stopped at the end of one revolution by clutch disengagement and brake application comprising a horizontally disposed blank feeding table mounted on the mill in alignment with the roll gap, said table having an opening therein spaced horizontally from the roll gap a distance corresponding substantially to the length of the portion of the blank which is to be rolled, a blank guide mounted on the table to direct advancing blanks longitudinally of the table in alignment with said opening, a trip pivotally mounted beneath the table having its upper end biased upwardly through said opening into the path of a blank being advanced along said table to the roll gap, said trip mounted for movement downwardly about its pivot in response to engagement with the leading end of a blank being advanced toward the rolls, said trip being maintained in said downwardly disposed position by engagement with the underside of the blank over the opening, said trip being spring biased upwardly to its projecting position in response to the trailing edge of the blank passing beyond the trip in its movement toward the roll gap, brake and clutch control means including a first valve operatively connected to the trip and moved thereby and a second valve connected by a fluid pressure conduit to said first valve, said second valve having a movable member therein spring biased to a position establishing fluid flow from said conduit through the valve, said second valve having a piston therein connected to said movable member responsive to fluid pressure from said conduit to hold said member in a position interrupting fluid flow through said second valve, cam means turning with said rolls, a cam follower connected to said valve member to move said member against the action of said spring to interrupt fluid flow through said second valve.
